UNITED STATES PATENT OFFICE.

JOHN L. REMLINGER, OF PROVIDENCE, ASSIGNOR TO WILLIAM A. BEATTY,
OF PAWTUCKET, RHODE ISLAND.

DESIGN FOR SCARF-PIN OR SIMILAR ARTICLES OF JEWELRY.

Specification forming part of Design No. **11,461**, dated October 14, 1879; application filed September 1, 1879.
[Term of patent 3½ years.]

To all whom it may concern:

Be it known that I, JOHN L. REMLINGER, of Providence, in the county of Providence and State of Rhode Island, have originated a new Design for Articles of Jewelry, of which the following is a specification:

My design relates to articles of jewelry; and consists of an ornamental head for a scarf-pin, scarf-ring, and other similar articles.

The accompanying drawing is hereby made part of this specification.

The design, as exhibited in the accompanying drawing, comprises the figure of a human skeleton having one arm extended, the hand of which clutches and exhibits the four aces of a pack of common playing-cards. The attitude and expression of the figure are strongly exultant as it displays its "winning-hand;" and suited to this is the position of the unoccupied arm, which reaches significantly for the stake of the game.

The device is to be made of the materials common for articles of jewelry, and its effect will be heightened by appropriate coloring and finish. The figures on the four cards are to be enameled or otherwise finished in colors respectively appropriate to them.

On the cards on which the finished design is to be mounted for sale I purpose to print, immediately over the figure, an appropriate or popular phrase or saying, such as "Pass in your chips," &c.

Instead of the four cards held as aforesaid, I intend sometimes to represent the figure as holding an opened fan, in which case I purpose to make a corresponding change in the phrase or saying printed on the card, such as some reference to the heated term; &c.

I claim as my design, and desire to secure by Letters Patent—

A design for a scarf-pin, scarf-ring, or other similar article of jewelry consisting of the figure of a skeleton having an extended arm and hand which clutches and displays the four aces of a pack of common playing-cards, the other hand reaching significantly for the stake of the game, all in the manner substantially as described, and shown in the accompanying drawing.

JOHN L. REMLINGER.
